UNITED STATES PATENT OFFICE.

FRANK D. MASTERSON, OF BOSTON, MASSACHUSETTS, ASSIGNOR TO
CHASE-SHAWMUT CO., OF BOSTON, MASSACHUSETTS, A CORPO-
RATION OF MAINE.

RAIL-BOND.

No. 839,072.

Specification of Letters Patent.

Patented Dec. 18, 1906.

Application filed October 2, 1905. Serial No. 280,884.

To all whom it may concern:

Be it known that I, FRANK D. MASTERSON, of Boston, county of Suffolk, State of Massachusetts, have invented an Improvement in 5 Rail-Bonds, of which the following description, in connection with the accompanying drawings, is a specification, like characters on the drawings representing like parts.

Rail-bonds of the type comprising several 10 layers or flat strips of copper secured together at their ends, but disconnected along their intermediate portions, are quite largely used, being usually soldered to the rails. The intermediate portion of the rail-bond is bent 15 in diverse ways, according to circumstances and conditions, and is intended to be sufficiently flexible or extensible to provide for the expansion and contraction of the rails and also for any other movement of the rails 20 relative to each other.

In practice it has been found that when the end of one of the rails is considerably higher than the end of the adjoining rail and a wheel passes quickly over the two rails the 25 intermediate portion of the rail-bond is so violently and suddenly extended or otherwise moved that the outermost layer or strip becomes separated more or less from the remaining layers or strips, and as this action is 30 repeated said layer or strip gradually becomes distorted, and then the next layer or strip likewise becomes separated from the remaining layers or strips and becomes distorted, and so on, and as a result the rail-bond 35 finally becomes a source of great trouble. Furthermore, in some instances the intermediate portion of the rail-bond occupies a position so close to the adjoining end of the rails as to contact therewith, and in such case 40 said intermediate portion is injured by the burs, fins, or other forms of projections which frequently extend laterally from the ends of the rails. Such rail-bonds are also liable to 45 injury from various other causes.

This invention has for its object to provide 50 this type of rail-bond with means for holding the several layers or strips comprising the intermediate portion in proper relative position, so that they cannot become separated 55 and subsequently distorted in the manner described, and also to provide a protection against injury from other causes.

The invention consists in a rail-bond comprising several layers or flat strips secured to-

gether at their ends and disconnected along 55 their intermediate portion and a band passed around the intermediate portion of the rail-bond, which is attached to one of the layers or strips—as, for instance, to the outermost layer or strip—thereby permitting free sliding movement of the several layers or strips relative to each other, yet holding them confined sufficiently to provide against undue separation.

Figure 1 shows in side elevation a rail-bond 65 having means embodying this invention for holding the layers or strips composing the intermediate portion thereof against undue separation, yet permitting free movement thereof to a certain extent. Fig. 2 is a 70 transverse section of the rail-bond, taken on the dotted lines 2 2, Fig. 1.

The rail-bond herein shown is composed, essentially, of several layers or strips *a*, of copper, attached together at their ends and 75 disconnected along their intermediate portions, thereby producing a flexible or extensible intermediate portion between the points of attachment of the rail-bond. Around the intermediate portion of the rail-bond a band 80 *b* is passed, the ends of which are secured by solder or otherwise to one of the layers or strips—as, for instance, to the outermost layer or strip, as at *b'*—said band being disconnected from all the other layers or strips. 85 The band *b* does not embrace the intermediate portion so tightly as to bind the layers or strips together sufficiently to prevent free sliding movement of its several layers or strips relative to each other, and therefore 90 the intermediate portion may respond to the varying relative conditions of the rails. The band *b* is preferably made of copper, although it may be made of any other suitable material. The band when applied to the intermediate portion of the rail-bond holds the 95 several layers or strips composing said intermediate portion from undue separation and also protects them from injury incident to engaging burs, fins, or other projections 100 which extend laterally from the adjoining ends of the rails.

It is obvious that the band may be applied to rail-bonds of other construction than that herein shown having intermediate portions 105 composed of disconnected layers or strips when it is desired to overcome the objections above noted.

Having thus described my invention, what I claim as new, and desire to secure by Letters Patent, is—

A rail-bond having an extensible intermediate portion composed of several disconnected layers or strips and a band embracing said intermediate portion which is attached to one of said layers or strips, permitting a sliding movement of the several layers or strips relative to each other but preventing

their undue separation, substantially as described.

In testimony whereof I have signed my name to this specification in the presence of two subscribing witnesses.

FRANK D. MASTERSON.
